(57) **CLAIM**

The ornamental design for a display screen with graphical user interface, as shown and described.

DESCRIPTION

FIG. 1 is a front elevational view of a first embodiment a display screen with graphical user interface showing our new design.

FIG. 2 is a front elevational view of the second embodiment thereof; and,

FIG. 3 is a front elevational view of the third embodiment thereof.

The broken lines showing the display screen are provided for the purposes of illustrating portions of the article and form no part of the claimed design.
